Primary Examiner — T Chase Nelson*Assistant Examiner* — Jonathan J. Han(74) Attorney, Agent, or Firm — KA Filing LLC; Wayne V. Harper(57) CLAIM

I claim the ornamental design for an outsole, as shown and described.

DESCRIPTION

FIG. 1 is an enlarged rear view of the outsole, showing my new design;

FIG. 2 is an enlarged front view thereof;

FIG. 3 is a top perspective view of the outsole seen in FIG. 1;

FIG. 4 is a right side view of FIG. 1;

FIG. 5 is a left side view of FIG. 1;

FIG. 6 is a top view of FIG. 1; and,

FIG. 7 is a bottom view of FIG. 1.

The broken lines in the drawing are used to illustrate portion of the outsole that form no part of the claimed design.
